COMBINED RADIO AND INTERCOMMUNICATION UNIT

John R. Young, Dallas, Tex.

Application June 17, 1955, Serial No. 36,571

Term of patent 14 years

(Cl. D26—14)

Fig. 1.

Fig. 2.

Fig. 1 is a front elevational view of a combined radio and intercommunication unit showing my new design; and Fig. 2 is a front perspective view thereof.

I claim:

The ornamental design for a combined radio and intercommunication unit, substantially as shown.
